UNITED STATES PATENT OFFICE.

THOMAS FREDERICK ROBINSON AND FRANCIS SMITH, OF LITTLE FALLS,
NEW YORK.

AUTOMATIC FIRE-ALARM.

SPECIFICATION forming part of Letters Patent No. 591,009, dated October 5, 1897.
Application filed February 1, 1897. Serial No. 621,474. (No model.)

To all whom it may concern:

Be it known that we, THOMAS FREDERICK ROBINSON and FRANCIS SMITH, citizens of the United States, residing at Little Falls, in the county of Herkimer and State of New York, have invented certain new and useful Improvements in Automatic Fire-Alarms, of which the following is a specification.

This invention relates to automatic fire-alarms; and the objects of our improvements are to provide a simple, inexpensive, and reliable fire-alarm which will promptly give an alarm the instant the temperature in a room reaches a predetermined point and which may be conveniently and cheaply reset.

Our invention consists, essentially, in a device which will automatically close the circuit in an electric alarm system when the surrounding temperature reaches a certain limit, and is adapted to form a part of such a system without interfering in the least with the working of the different appliances which may form the other part of the said system.

Referring to the accompanying drawings, Figure 1 is a sectional view of the invention, showing the normal position of the parts. Fig. 2 is a similar view of the device, showing the position of the parts as they appear when the surrounding temperature has reached a predetermined point. Fig. 3 is a plan view of the device. Fig. 4 is an elevated view of the plunger.

Similar letters refer to similar parts throughout the different views.

A represents the base-plate of the device, preferably made of wood or some other insulating material. This base-plate is adapted to be attached to the wall or ceiling by means of four screws A', and is provided with a centrally-located, hollow portion A². This hole or hollow portion has a reduced portion A³ at its forward end for the purpose hereinafter described.

B represents two binding-posts provided with two screws B', which are screwed into opposite sides of the said base-plate and extend with their points into the hollow portion A².

C represents two conducting-wires leading to the electric alarm system. These wires are connected in the usual manner to the binding-posts and permit the electric current to

pass through the screws when a contact is simultaneously established with the points of the screws by means of a conductor.

D represents a plunger which is slidably mounted in the reduced hollow portion of the base-plate and is provided at one end with a piston D', adapted to form a circuit-closer when the plunger is in a released position.

This piston also acts as a shoulder for a spiral spring E, which is interposed between the piston and the said reduced hollow portion of the base-plate, and is adapted to exert a pressure upon the piston. The end portion of the piston is made conical in order that it may easily adjust itself into contact with the projecting ends or points of the screws B' when the plunger is forced toward them.

F represents a pin or stopper capable of being bent, broken, fused, or practically destroyed when exposed to a predetermined temperature. This pin extends first through a staple G, secured to the front side of the base-plate, and then through a hole D² in the plunger, and is adapted to normally hold the plunger back against the tension of the spiral spring and prevent the conical end portion of the piston from coming in contact with the points of the screws. In order to limit the amount of projection of the pin in the hole of the plunger, the pin is provided with a head F', which engages the staple when the desired limit of projection has been reached.

In order to prevent the material of the pin when the same gives away from becoming wedged between the plunger and the reduced hollow portion of the base-plate, the forward portion of the plunger is reduced. This reduced portion terminates in a knob D³, which enables one to obtain a good grip of the plunger when the same is to be pulled out for the purpose of renewing the pin.

When the temperature reaches a predetermined point, the resistance of the pin is destroyed, and thus permits the plunger to be actuated by the spring and forced toward the points of the screws and the conical end portion of the piston to adjust itself into contact with the same, and by so doing closes the circuit in the electric alarm system and gives the alarm.

The operation of resetting the device is accomplished by simply taking hold of the knob

and pulling the plunger out, so that the hole of the same will be situated in line with the opening formed by the staple, in which position the pin is first pushed through the staple 5 and then the end portion of the pin inserted in the hole of the plunger.

We are aware that many changes may be made in the construction of our improved fire-alarm, and for that reason do not desire to 10 limit ourselves to the particular construction herein shown and described, but reserve the right to make such changes as would fairly come within the scope of our invention.

Having thus described our invention, what 15 we claim as new, and desire to secure by Letters Patent, is—

In an automatic fire-alarm, the combination with the insulating base-plate, said base-plate being provided with a centrally-located hollow 20 portion, the forward end of said portion being reduced so as to form a square shoulder, two conductors, forming part of an electric alarm system, extending into said hollow portion, a plunger slidably mounted in said 25 hollow portion, said plunger being provided

at its rear end with a piston having a longitudinal guiding-surface and a conical end portion, a spiral spring interposed between the piston and the said shoulder in the hollow portion of the base-plate, the forward portion of the said plunger being reduced and terminating in a knob, a hole extending through the thick portion of the plunger adjacent to the reduced portion thereof, a pin capable of being destroyed when exposed to 30 a predetermined temperature, partly extending through said hole, said pin being provided with an enlarged portion or head, a staple or guide located on the front surface of the base-plate, engaging said head of the pin, substantially as described and for the purpose set forth.

Witness our hands this 18th day of January, 1897.

THOMAS FREDERICK ROBINSON.
FRANCIS SMITH.
